UNITED STATES PATENT OFFICE.

MARTIN W. KIEFER, OF HELFENSTEIN, PENNSYLVANIA.

HARVESTER CUTTER-BAR.

SPECIFICATION forming part of Letters Patent No. 288,342, dated November 12, 1883.

Application filed July 10, 1883. (No model.)

To all whom it may concern:

Be it known that I, MARTIN W. KIEFER, a citizen of the United States, residing at Helfenstein, in the county of Schuylkill and State of Pennsylvania, have invented certain new and useful Improvements in Harvester Cutter-Bars; and I do hereby declare the following to be a full, clear, and exact description of the invention, such as will enable others skilled in the art to which it appertains to make and use the same.

My invention has relation to the cutting mechanism of reaping and mowing machines, and is designed in part to enable the operator to quickly and easily remove one or more of the sickle-blades from the cutter-bar and replace it with another. To do this the only tool required is a small screw-driver. In the event of an accident in the field, by which a blade is broken or injured, the exchange is made in a few moments and the work proceeds at once. Furthermore, the sickle-blades may all be readily taken out, when desired, for sharpening or other purposes, and there are no small parts liable to be lost, the screws which hold the parts together being only partly withdrawn.

A part also of my invention consists in the means I employ to connect the frame of the cutter-bar to the pitman or vibrating rod of the machine.

The drawings which accompany this specification fully illustrate the various features of my invention, the different parts of which are referred to by letters, similar letters indicating corresponding parts in the several views.

In the drawings, Figure 1 is a plan view of a part of my invention, a portion being broken away. Fig. 2 is a front elevation. Fig. 3 is an enlarged cross-sectional view on the line α of Fig. 1. Fig. 4 shows one of the teeth or sickle-blades of my cutter-bar, enlarged. Fig. 5 represents a part of the cutter-bar with two teeth in position. Fig. 6 is a plan of the end of the frame of the cutter-bar inverted and enlarged. Fig. 7 represents another form of pitman-coupling used on my cutter-bar.

I form my cutter-bar in three pieces, which are detachably connected together. They are an upper bar, A, a lower bar, B, which latter underlaps the end frame C, the third piece. A curved rib, D, is formed on the frame C, which strengthens the said frame and supports a hol-

low ball, E, to which the pitman F is connected. A recess, c, is provided in the under side of the frame C, (see Fig. 6,) the broader part, c', of said recess accommodating the butt ends of the cutting-blades. The bar or strip B fits into the recess c, and is secured to the frame C by the bolts and nuts d d and the holes d' d' through the bar B and the frame C. The heads of the bolts d are preferably sunk in the bar B. This lower bar, B, has formed on its upper side the fixed diamond-shaped blocks b b, (see Fig. 5,) at proper intervals to receive between them the blades G G. On each side of the base of each sickle-blade G is provided a recess g g, adapted to fit snugly against the side of the block b b. (See Fig. 5.) The height of the blocks b is equal to the thickness of the blades G. The strip or bar A, of about equal width and thickness with the bar B, extends from the frame C, parallel with the bar B, and is designed to securely hold the blades G in operative position. Threaded holes a a, through the bar A, the blocks b and lower bar, B, are provided for the screws I I, by which these parts are firmly held together. (See Fig. 3.) The notches g g in the blades G and the blocks b b are made of uniform dimensions, so that any of the blades will fit between any two of the blocks. This arrangement of the strips and frame give strength and firmness to the bar, and hold the cutting-blades firmly when the machine is in operation.

The pitman F, Fig. 1, is furnished with two arms, one of which, l, is fixed upon the pitman F, and the other, l', is pivoted to the said rod or pitman. These arms l l' are broadened at their working ends and formed into sockets, which, as the arms are brought toward each other, close upon the ball E, in which position they are held by the set-screw m. The ball E is preferably made hollow, to secure greater lightness, and a supply of oil in its concavity will lubricate its exterior through the small opening e.

To take out all the teeth from the cutter-bar, the top piece, A, is generally taken off; but to remove a single tooth the screws on either side of its base are drawn up sufficiently to permit the screw-driver to be thrust in between the upper strip and one of the blocks b. Using the screw-driver as a lever the upper strip, A, is then raised sufficiently to allow the tooth to

be lifted from its bed, when by moving it to one side until the notch *g* encounters the screw *I* the other corner of the base will pass the other screw, and the tooth is readily drawn 5 out at the front of the cutter-bar. By the same movement reversed another tooth is inserted, and the strip *a*, which should be of steel, when released, closes down upon the tooth, and the screws are again put in place. Both 10 of the bars *A* and *B* are preferably made of steel; but other material may be used, if desired, and I do not confine myself to the use of any particular material in constructing any of the parts of my invention.

15 I am aware of patents granted to Arnold June 29, 1875, No. 164,958; to Hover April 29, 1856, No. 14,768; to Crees July 19, 1881, No. 244,435, and to Tilley & Sanford January 2, 1883, No. 269,899, for cutting apparatus, 20 and do not claim them as my invention.

Having now described my invention, what I claim, and desire to secure by Letters Patent of the United States, is—

In a cutter-bar, the combination of the strip or bar *A*, having screw-holes *a a*, the strip or bar *B*, having the fixed elevations or blocks *b b* and threaded holes *a' a'*, the end frame, *C*, having recesses *c c* and holes *d d*, the bolts and nuts *d d*, the screws *I I*, the sickle-blades *G G*, having the angular recesses *gg*, and suitable means for connecting the cutter-bar to the pitman *F*, all constructed substantially in the manner and for the purposes herein set forth.

In testimony whereof I affix my signature in 35 presence of two witnesses.

MARTIN W. KIEFER.
